FLUID APPLICATOR

Jerome W. Turley, East Orange, N. J., assignor
of one-third to Eugene G. Cicchetti and one-
third to Samuel Bahoush, both of East Orange,
N. J.

Application December 8, 1949, Serial No. 131,838

1 Claim. (Cl. 128—226)

1
This invention relates to novel articles of manufacture. In one of its more specific aspects the invention is directed to novel devices which may be employed for the administration of vaginal douches, for the administration of enemas, etc. In another of its aspects the novel devices are of such design that certain of their demountable parts may be detached therefrom and the remaining fluid retainer or bag may be used as a hot water bag, an ice collar, bed tube, sitting tube for wheel chair patients, etc.

An object of the present invention is to provide novel devices which do not require anyone other than the user for the administration of vaginal douches or enemas.

Another object of this invention is to provide such novel devices which may serve a great variety of purposes either in the home or in hospitals.

Still another object of this invention is to provide devices of the type referred to which are of simple construction, relatively small in number of parts, relatively inexpensive and easy to keep clean.

These as well as other objects and advantages of this invention will be readily apparent from the following description and appended drawings, wherein:

Fig. 1 is a top plan view of a device embodying the invention.

Fig. 2 is a view mainly in cross section on line 2—2 of Fig. 1, but with the nozzle being shown in plan view.

Fig. 3 is a cross sectional view illustrating a modification of the connection shown in Figs. 1 and 2.

According to this invention, there is provided a hollow endless collapsible tube 10 which may be in the form of an annulus. The seamless annular member 10 may be in the form of a relatively thin walled tube having an enlargement or rib 11 extending around the entire circumference thereof at the outer central part thereof. The tube 10 with the rib 11 may be composed of any desired material, such as rubber or any desired plastic material composed of resins of the polyvinyl type. The lower face of the annular tube 10 has an inlet opening therethrough carrying a sealed interiorly threaded bushing ring 12 for accommodating a demountable screw stopper or cap 13. The inner periphery of the annular tube 10 has an outlet opening and at said outlet opening is an inwardly extending short discharge tube 14 integral with tube 10 and composed of the same material as tube 10.

2
A unitary discharge hose and fluid-control combination 15 may be demountably connected to the tube 10. This combination comprises a rigid connector 16 one end of which extends into the outer end of tube 14 and makes a frictional liquid-tight seal therewith. This connector 16, which may be composed of any suitable plastic material or metal, has its outer end exteriorly threaded. A rigid housing 17 is in the form of a cylinder having an inwardly extending annular flange or shoulder 18. A hard rubber ball 19 is located in said housing 17 and maintained in fixed location by a pin 20 extending therethrough with its ends extending into and secured to the housing 17. A flexible rubber tube 21 extends through the opening of the annular member 18 and has a shoulder 22 at one end thereof bearing against annular member 18. A rubber washer or grommet 23 is located in the housing 17 and is in frictional engagement with the interior thereof. The washer 23 is spaced from the ball 19 and bears against shoulder 22 to maintain shoulder 22 firmly against annular member 18 to assure a fluid-tight seal between shoulder 22 and member 18 at all times. The other end of the housing 17 is interiorly threaded and makes threaded engagement with the threaded outer end of member 16. The outer end of the tube 21 has a nozzle 25 of appropriate design demountably coupled therewith by frictional engagement as shown.

Instead of having a discharge tube 14 extending outwardly from the inner circumference of tube 10 and making frictional engagement with the inner end of tube 16 as shown in Fig. 1, tube 14 may be completely eliminated as shown in Fig. 3. In such a case, I provide a threaded bushing 30 in place of tube 14 and the inner end as well as the outer end of connector 16 is threaded so that the inner end thereof makes threaded engagement with bushing 30 for readily connecting to and disconnecting from the assembly 15 with respect to the tube 10.

In use when the device is to be used for administration of a vaginal douche or enema, the cap 13 of the device, as shown in Figs. 1 and 2 or modified as shown in Fig. 3, is first removed and the tube 10 is filled through bushing 12 with the desired fluid. Then the person to be treated may in either sitting or lying position rest her buttocks upon the tube 10 and insert the nozzle 25 into the appropriate body cavity. Then the housing 17 is rotated to move the ball valve 19 away from the end of the tube 16, which it closes in the position shown in Fig. 2, to thus permit the passage of

fluid from tube 10 into and through tube 21 and nozzle 25. The weight of the body resting upon the collapsible tube 10 places the fluid under sufficient pressure to force the fluid up to and through nozzle 25. The rate of fluid flowing through nozzle 25 is controlled by rotation of the housing 17. After the desired amount of fluid has been expelled through nozzle 25, any further flow of fluid may be stopped by merely rotating the housing 17 in the opposite direction to force the ball 19 back against the bevelled end of the tube 16.

While one may sit or lie on the tube 10 to apply pressure to the fluid therein, the tube 10, if desired, may be placed on a support and pressure applied thereto by the user by placing the forearms on top of the tube 10. This as well as a variety of other alternate methods may be employed by the user for providing a fluid flow from tube 10.

If desired, the entire assembly 15 may be detached from the tube 10 and the tube 14 or bushing 30 may be closed by a suitable stopper or cap (not shown) and the tube 10 may now be used as a hot water or ice bag, or the like.

While this invention has been described in detail, it is not to be limited to the exact construction shown, because various changes and modifications may be made within the spirit of the invention as defined by the claim in this application.

I claim:

A device of the character described comprising an annular hollow body formed of compressible material and constituting a collapsible liquid container, said container being formed with an

outlet through its inner peripheral portion, a coupling having inner and outer sections open at their ends, the inner section having its inner end portion secured in the outlet of said body and being externally threaded from its outer end, the outer section being internally threaded from its inner end and screwed upon the outer end portion of the inner section, an internal annular flange about the outer end of the outer section defining an opening therein, a ball in said outer section secured by a pin passing diametrically through the ball with its ends fitting into openings formed in diametrically opposed wall portions of the outer section, said ball constituting a closure movable into and out of a closed position against the outer end of the inner section by screwing the outer section onto and off of the inner section, a hose having its inner end portion passing through the opening at the outer end of the outer section and formed with a shouldered portion fitting between the flange and the confronting portion of the ball, and a nozzle at the outer end of said hose.

JEROME TURLEY.
